UNITED STATES PATENT OFFICE.

CUGE L. McCRAY, OF PORTSMOUTH, OHIO.

RAILWAY-TIE AND FASTENER.

1,083,626.

Specification of Letters Patent.

Patented Jan. 6, 1914.

Application filed October 8, 1913. Serial No. 794,080.

To all whom it may concern:

Be it known that I, CUGE L. McCRAY, a citizen of the United States, residing at Portsmouth, in the county of Scioto and State of Ohio, have invented certain new and useful Improvements in Railway-Ties and Fasteners, of which the following is a specification, reference being had to the accompanying drawings.

This invention relates to new and useful improvements in railway ties and fasteners and more particularly to a metallic sectional tie, and rail fastener, the object of the invention being to provide a metallic tie formed in sections, each section being provided with recesses to receive the base flanges of the rails and further provided with means to accommodate fastening members whereby the rails will be securely held in position.

Another object of the invention is the provision of a metal tie and fastener of the above character which will possess advantages in points of efficiency and durability, is inexpensive of manufacture and at the same time is simple in construction and operation.

With the above and other objects in view, the invention consists in the novel features of construction and the combination and arrangement of parts to be hereinafter more fully described, pointed out in the claims and shown in the accompanying drawings, in which—

Figure 1 is a side elevation of a rail constructed in accordance with my invention; Fig. 2 is a top plan view; Fig. 3 is a horizontal sectional view taken near the bottom of the tie; Fig. 4 is a bottom plan view; Fig. 5 is a horizontal sectional view of the fastening members taken above the top of the tie; Fig. 6 is a transverse sectional view of the tie; Fig. 7 is an end elevation; Fig. 8 is a transverse sectional view on the tie, the fastening members being removed; Fig. 9 is a detail perspective view of one of the fastening members; Fig. 10 is a detail perspective view of a portion of the tie illustrating one end of the transverse recess.

In carrying out my invention, I provide a U-shaped member which is formed in two sections 1 and 2, each section comprising an angular member which when arranged in position, constitutes the base and side walls of the tie. The horizontal edges of each section of the tie are provided with spaced recesses 3 which form outwardly projecting

tongues 4 so that when the two sections are arranged in position, the tongues upon each section will fit within the recesses of the opposite section, thus securely holding each section against longitudinal movement.

The ties are provided adjacent each end thereof and in the upper edges of the side walls with recesses 5 having tapering side walls 6 which are formed coincident with the inclination of the base of the rails. The side walls of the recesses 5 are cut away at their upper ends to form holders 7 having inclined side walls 8, the purpose of which will be more fully set forth herein-after. Arranged within each end of the ties and disposed between the recesses 5 are the supporting blocks 9 upon which the rails are adapted to rest when arranged in position so that all of the weight of the rails will not be thrown entirely upon the side walls of the ties.

My improved fastening members each comprise a substantially rectangular body member, one edge of which is bifurcated, as shown at 10, to form the spaced arms 11 having alined openings 12 formed therein, for the reception of the retaining bolts 13 which extend through the tie and through the openings 12 to retain the fastening members in position. Formed integral with the opposite end of the body member is an enlarged head 14, one face of which is provided with a tapering portion 15 which is formed coincident with the inclination of the base of the rails and adapted to fit tightly thereon. A vertical portion 16 is also formed on the same face of the head and is adapted to abut against the web of the rail, as clearly illustrated in Fig. 1. Projecting outwardly from each side of the body member and formed integral with the head portion 14 are the tongues 17, the rear faces of which are tapered, as shown at 18, and are adapted to rest upon the shoulder 19 and fit tightly against the inclined walls 8. A second retaining bolt 13' is arranged upon each side of the rail and arranged above the first retaining bolts 13. These bolts 13' are arranged within suitable openings in the side walls of the tie adjacent the upper edge thereof and when in position are engaged with the outer faces of the fastening members so as to prevent any movement of the upper ends of the fastening members when in position. From this it will be seen that after the rails

have been arranged within the recesses 5, the fastening members designated generally by the numeral 19 are quickly arranged in position by inserting the body portion there-
5 of between the side walls of the tie and ar-
ranging the bolts 13 in position. The up-
per ends of the fastening members are then
placed in position and the bolts 13' inserted
through the openings within the upper
10 edges of the side walls so as to prevent any
outward movement on the part of the fas-
tening members. It will be noted that by
having the inclined walls 18 of the tongues
17 engaged beneath the inclined walls 8, it
15 will prevent any outward movement what-
ever on the part of the fastening members
and at the same time will securely retain the
enlarged head portions 14 into engagement
with the base and web of the rails.
20 From the above description taken in con-
nection with the accompanying drawings, it
will be readily apparent that I have pro-
vided a simple and durable metallic railway
tie which is preferably formed in two sec-
25 tions, the lower horizontal portions of which
are provided with alternating grooves and
tongues and are further provided with re-
cesses to receive the rails. It will also be
30 apparent that the tie in itself is extremely
simple in construction and the rail fasten-
ers can be quickly and readily applied there-
to after the rails have been arranged in po-
sition.

While I have shown and described the
35 preferred form of my invention, it will be
obvious that various changes in the details
of construction and in the proportions may
be resorted to for successively carrying my
invention into practice without sacrificing
40 any of the novel features or departing from
the scope of the appended claims.

Should it be desired to use the rails for
conducting a current to an electric motor
car or the like, it will be understood that
45 the rails are to be insulated from the ties

and fastening means by means of mica or
other suitable insulating material.

What I claim is:—

1. A railway tie including angular sec-
tions having continuous alternating grooves 50
and tongues formed in the horizontally dis-
posed portions thereof, as and for the pur-
pose set forth.

2. A device of the class described includ-
ing a U-shaped tie having recesses formed in 55
the upper edges of the side walls thereof,
shoulders formed upon each side of the re-
cesses and provided with inclined walls, fas-
tening members each comprising a body
having spaced perforated ears at one end 60
and adapted to be inserted between the side
walls of the tie, bolts extending through
said side walls and ears to secure said fas-
tening members in position, outwardly pro-
jecting tongues formed at the upper end of 65
the body upon each side thereof and having
inclined portions adapted to engage the in-
clined portions formed in said side walls,
as and for the purpose set forth.

3. A device of the class described includ-
ing a U-shaped sectional tie, fastening mem-
bers each comprising a body having spaced 70
perforated ears at one end and adapted to
be inserted between the side walls of the tie,
bolts extending through said side walls and 75
ears to secure said fastening members in po-
sition, and a second set of bolts extending
through the side walls of the tie arranged
above the first set of bolts in an offset po-
sition and against which the outer faces of 80
the fastening members are adapted to abut
to retain said fastening members into en-
gagement with the base of the rails.

In testimony whereof I hereunto affix my
signature in the presence of two witnesses. 85

CUGE L. McCRAY.
